VACUUM COOLING UNIT

Lawrence M. Fornecook, Pittsburgh, Pa., assignor
to Elliott Company, Pittsburgh, Pa., a corpora-
tion of Pennsylvania

Application June 13, 1934, Serial No. 730,459

7 Claims. (Cl. 62—152)

Figure 1 is a side elevation showing one form of apparatus constructed in accordance with my invention;

Figure 2 is a diagrammatic vertical section on a smaller scale illustrating the operation; and

Figure 3 is a view similar to Figure 2 showing a modified form similar to that of Figures 1 and 2, except that a tubular or surface condenser is used therein.

10 My invention relates to vacuum-cooling apparatus of the steam jet type and is designed to simplify, cheapen and improve such apparatus. In Figures 1 and 2 of the form shown in the drawings, a single tank or cooling unit indicated

15 generally by the letter A is divided into two chambers indicated generally by the letters B and C. The upper head 2 is provided with a central steam-expanding nozzle 3 below and in line with which is a central diffuser having the upper

20 downwardly contracting portion 4 within the upper chamber and the lower downwardly expanding portion 5 within the lower chamber. The chambers are separated by a partition which preferably contains insulation, being shown as

25 consisting of two plates 6 and 7 separated by an air space. I have also illustrated the upper portion 4 of the diffuser as insulated by surrounding pipe or nozzle 8 with an air jacket between it and the portion 4. Of course, any suitable insulation

30 may be provided in either case. Intermediate the height of the upper chamber B an annular water spillway 9 is provided having inlet 10 for the refrigerant or water to be cooled. Just above the partition between the two chambers B and C is an outlet 11 for the cooled or chilled water which collects on the top of the partition.

The lower chamber is provided with an upper outlet 12, leading to a secondary vacuum device such as the motor-driven vacuum pump 13, shown

40 in Figure 1 as mounted on the shell and driven by electric motor 14. This, of course, may be replaced by any other type of vacuum device, such as a steam jet ejector. The lower chamber is provided with an internal annular water spillway

45 15, below which a series of staggered annular baffles generally numbered 16 are arranged.

The lower head 17 of the shell is provided with an outlet pipe 18 for removal of the condensing water and condensed steam. The pipes 11 and

50 18 may lead to centrifugal pumps 19 and 20, or

these pumps may be omitted where gravity draining is possible. The spillway 15 is supplied with condensing water through inlet 21.

As will be noted, the inlet 10 and the outlet 11

55 of the evaporator chamber are located behind the

mouth of the diffuser portion 4 in the sense of downstream from such mouth when considering the flow of fluid through the diffuser. In like manner, the inlet 21 and the outlet 12 of the condenser chamber are located behind the mouth of the diffuser portion 5 in the sense of upstream from such portion when considering the flow of fluid therethrough. It will also appear that the inlets and outlets of both the evaporator and condenser chambers are located upstream from the mouth of the diffuser portion 5. The flow directed by the spillways in both the evaporator and condenser chambers is substantially longitudinal of the diffuser 4—5.

When in operation, steam of any desirable pressure is admitted and expanded through nozzle 3, thus changing pressure energy to velocity energy. A high velocity steam jet leaving this nozzle 3 entrains gas or vapors in chamber B, and the mixture is driven into the upper portion 4 of the diffuser. This reduces the pressure in chamber B and sets up a partial vacuum therein. The quantity of steam admitted through the nozzle 3, together with the design of this nozzle and of the diffuser, will result in creating any predetermined pressure in the upper compartment 20 B. The water to be cooled is either drawn in through opening 10, by reason of the reduced pressure, or is pumped in as conditions require; and this water spills over the annular weir 9, falls to the bottom of the upper compartment and is drained through pipe 11. As this water to be cooled enters the upper compartment and falls over the weir, it is subjected to a sub-pressure materially less than that corresponding to its entering temperature. The result is that a part of this entering water is immediately vaporized and these vapors are entrained by the steam jet leaving nozzle 3 and compressed in diffuser 4 and discharged into the lower compartment C. 40

The latent heat liberated by this vaporization of a part of the water to be cooled is withdrawn from the liquid as it falls over the weir 9. Consequently, the liquid passing out through opening 11 is of a temperature corresponding to the 45 sub-pressure created in upper chamber B. By a suitable design with proper proportioning and supplying the proper quantities of steam and condensing water, this unit may cool any desired quantities of water through any desired temperature range and produce chilled water at any desired temperature above the freezing point. Other liquids than water may be admitted through pipe 10 and drawn out through pipe 11, though water will be the liquid ordinarily used. 50 55

After the steam jet and entrained gas and vapors enter the diffuser, the velocity energy is reconverted into pressure energy and the mixture of propelling steam and entrained vapors is discharged from the lower end of the part 5 of the diffuser into the lower part of the chamber C where it is condensed. As shown, this is a direct contact condenser, the water admitted through opening 21 falling over annular weir 15 and striking the cascaded baffles 16 so as to mix with and condense in counter-current flow the steam discharged from the lower end of the diffuser.

The non-condensable gases are drawn off through opening 12 in the upper part of the lower chamber by any suitable device such as a motor-driven vacuum pump or a steam jet or other suitable device.

While I have shown a direct contact type of condenser in the lower chamber portions of the shell or tank in Figures 1 and 2 of the drawings, I also contemplate using an indirect tubular or surface type condenser provided with tubes in the lower chamber through which condensing water may be circulated to condense the steam and vapors. Such a form is shown in Figure 3 wherein parts similar to those of the embodiment of my invention shown in Figures 1 and 2 are marked with the same numerals with the suffix "a" added.

In this form, the condenser has tubes 22 connecting a pair of separate inlet and outlet chambers 23 and 24 at one side of the lower chamber C with a single compartment 25 at the other side of said chamber. In this form, the baffles 16a take the form shown extending alternately from opposite sides and preferably overlapping each other. In this surface type condenser, the cooling water is circulated from inlet compartment 23 through the tubes to compartment 25, and thence back to outlet compartment 24. The tubes, of course, extend on opposite sides of the diffuser 5a and through the shell of the compartment.

The advantages of my invention result from the cheapness, compactness and simplicity of the unit, all of which may be contained within one shell or tank. I thus materially reduce the cost by eliminating the conventional air or vapor chamber containing the ejector suction, also by eliminating flanged connections in the diffuser of the compressor, and also by doing away with numerous piping connections. The conventional construction of such apparatus requires two separate tanks, one containing the evaporator and one containing the condenser. In my apparatus, the arrangement is simple, compact and efficient. The insulation largely prevents the transmission of heat from the condensing compartment to the fluid being cooled and from the steam jet compressor to the fluid being cooled.

Within the scope of some of my claims, the two compartments may be in separate shells, but preferably in tandem relation, each chamber containing a portion of the diffuser. Obviously, my construction gives a very compact and low cost apparatus. So far as I know, I am the first to enclose the diffuser in such apparatus partly within the flash chamber and partly within the condensing chamber.

The tank may extend in a horizontal direction instead of vertically, as shown, other means for insulation may be employed, the tank and its parts may be made up by welding, riveting or otherwise, as desired, and other changes may be made without departing from my invention.

Instead of a single nozzle 3, as shown, several nozzles may be used as conventionally employed in a steam jet compressor.

In large capacity units, two or more diffusers, such as 4 and 5, may be employed, each equipped with its own nozzle 3 or group of nozzles, in order to reduce the overall length of the apparatus. In such case, the apparatus may be the same as now shown, except that there are two or more diffusers arranged in the successive or tandem 10 chambers shown.

Although not specifically illustrated in the accompanying drawings, the steam nozzle 3 may have its exterior surface insulated by any suitable means in order to prevent the transmission of 15 heat from the steam nozzle to the evaporating compartment.

I claim:

1. In a liquid cooling apparatus of the steam-jet-vacuum type, a housing enclosure, a partition dividing said enclosure into evaporator and condenser chamber portions, a diffuser extending through said partition and into said evaporator chamber and into said condenser chamber and being surrounded by said chambers, an 20 ejector opening into and extending into said evaporator chamber and cooperating with the portion of said diffuser located within said evaporator chamber to feed a pressure fluid thereto and produce a vacuum in said evaporator chamber, an 25 opening in the housing of said evaporator chamber providing an inlet for a liquid to be cooled, and means for condensing vapors fed to said condenser chamber by the portion of said diffuser located therein. 30

2. In a liquid cooling apparatus of the steam-jet-vacuum type, a housing enclosure, a partition dividing said housing enclosure into a condenser chamber and an evaporator chamber having a tandem relationship with respect to each other, 40 a diffuser extending through said partition through one end of said evaporator chamber and into said chamber, said diffuser also opening into and extending into said condenser chamber from the end thereof adjacent said evaporator chamber, an ejector opening into said evaporator chamber and cooperatively associating with the mouth of the diffuser portion extending therein, fluid inlet and outlet openings in the housing portion of said evaporator chamber, means feeding liquid to be cooled from the inlet opening substantially longitudinally with respect to the portion of said diffuser located within said evaporator chamber. 45

3. In a liquid cooling apparatus of the steam-jet-vacuum type, a housing enclosure, a partition dividing said housing into an evaporator chamber and a condenser chamber, a diffuser extending through said partition into one end of said evaporator chamber and into an adjacent end of said condenser chamber, said diffuser having a converging-diverging outline from said evaporator chamber to said condenser chamber, the throat of said diffuser being located adjacent said partition and cooperating with said partition and the housing of said evaporator chamber to provide a receptacle for liquid to be cooled, inlet and outlet openings in said evaporator chamber for the liquid to be cooled, an ejector opening into said evaporator chamber and cooperating with the mouth of the portion of said diffuser casing located therein to supply a pressure fluid thereto, insulation about the portion of said diffuser located within said evaporator and between said partition and said condenser chamber, and means 50

in said condenser chamber for condensing fluid supplied thereto from the mouth of the portion of said diffuser located therein.

4. In a condenser having a suitable housing 5 enclosure, a diffuser opening into and extending inwardly of said housing from one end thereof and being substantially surrounded thereby, a nest of cooling tubes in said housing arranged in a heat-transfer relationship with respect to 10 wall portions of said diffuser, and condensing fluid inlet and outlet openings in said housing, said nest of cooling tubes being connected to said inlet and outlet openings.

5. In a condenser having a suitable housing 15 enclosure, a diffuser opening into and extending inwardly of said housing from an end thereof and being substantially surrounded thereby, a nest of cooling tubes in said housing, said diffuser extending through said nest of tubes, condensing 20 fluid inlet and outlet openings in said housing, and partitions directing fluid flow through said tubes in a return path from said inlet to said outlet opening.

6. In a cooling apparatus of the steam-jet- 25 vacuum type, a housing enclosure, a partition dividing said housing enclosure into a condenser chamber and an evaporator chamber having a tandem relationship with respect to each other, a diffuser extending through said partition 30 through one end of said evaporator chamber and into said chamber, said diffuser also opening into and extending into said condensing chamber from an end thereof adjacent said evaporator chamber, an ejector opening into said evaporator 35 chamber and being arranged to cooperate with the mouth of the diffuser portion extending therein, fluid inlet and outlet openings in the

housing portion of said evaporator chamber, said openings being located downstream of the mouth of the portion of said diffuser located in said evaporator chamber, means feeding liquid to be cooled from the inlet openings substantially longitudinally with respect to the portion of said diffuser located within said evaporator chamber, the flow of liquid from said means being directed in such a manner that it will be downstream of the mouth of the portion of said diffuser located 10 within said evaporator chamber, and means opening into the housing of said condenser chamber and being arranged to supply means for condensing fluid entering said chamber through the mouth of the portion of said diffuser located 15 therein.

7. In an evaporator having a suitable housing enclosure, an ejector nozzle opening into and extending inwardly of said housing, a diffuser opening into and extending inwardly of said housing substantially oppositely with respect to said ejector nozzle, said diffuser casing forming with said housing a receptacle for a liquid refrigerant, said ejector nozzle and said diffuser being surrounded by said housing and having a substantially cooperative relationship with respect to each other such that said ejector will directly discharge pressure fluid into said diffuser to produce a vacuum in said housing, inlet and outlet openings in said housing for a liquid refrigerant, and a spillway in said housing, said spillway being arranged to receive liquid refrigerant from said inlet opening and to direct a stream of liquid refrigerant substantially longitudinally of the walls of said diffuser. 25 30 35
